UNITED STATES PATENT OFFICE.

HENRY MOECKER, JR., OF HOMewood, THEODORE THOMPSON, OF HARVEY, AND OTTO HAMMERMEISTER, OF HARVEY, ILLINOIS, ASSIGNORS TO AMERICAN STOVE COMPANY, OF ST. LOUIS, MISSOURI, A CORPORATION OF NEW JERSEY.

GAS-RANGE CONSTRUCTION.

Application filed February 5, 1925. Serial No. 7,030.

To all whom it may concern:

Be it known that we, HENRY MOECKER, Jr., THEODORE THOMPSON and OTTO HAMMERMEISTER, all citizens of the United States, residing at Homewood and Harvey, respectively, in the county of Cook and State of Illinois, have invented new and useful Improvements in a Gas-Range Construction, of which the following is a specification, reference being had therein to the accompanying drawings.

This invention relates to improvements in gas range construction whereby the parts forming the construction are capable of use in a right hand or a left hand oven range.

Heretofore it has been necessary in constructing right and left hand oven ranges to have special parts for the two ranges, and it is one of the objects of this invention to so construct the parts as to adapt them for either a right hand or a left hand oven range, thus avoiding the expense heretofore necessary to construct these parts differently, and to avoid the necessity of carrying in stock parts for a left hand and parts for a right hand oven range.

Gas oven ranges as now constructed are provided with open burners at either the right or left hand side of the oven, and are provided with a backing usually enameled located in rear of the open burners, the said backing provided at its top with an inwardly extending top shelf.

A further object of the present improvement is to provide a top shelf support that is so constructed that it can be used for supporting the shelf for either a right or a left hand oven range, which so far as we are aware is new.

A further object of the present invention is to so construct this reversible part that it is adapted to receive an inwardly extending reversible bracket for supporting the said top shelf.

Another object of the present improvement is to so construct the support that it is adapted to permit the passage of the gas pipe or manifold for either a right hand or left hand oven range.

In carrying out the above objects the said support is adapted for either a right or left hand oven range by simply turning the part end for end, that is to say, when using the part for a left hand range, in

order to use the same part for a right hand oven range it is only necessary to turn it end for end when it will act for a range with the oven at the reverse side and in either position the reversible part is adapted to fit on the cooking top.

In the accompanying drawings:

Figure 1 is a perspective view of a right hand oven range with the improved parts applied thereto.

Fig. 2 is a sectional view on the line 2—2 of Fig. 1.

Fig. 3 is a rear perspective view of the parts shown in separated relation.

Fig. 4 is a sectional view on the line 4—4 of Fig. 1.

Fig. 5 is a sectional view on the line 5—5 of Fig. 1.

In Fig. 1 the gas range is shown with an oven 1 at the right and a burner top 2 at the left of the oven. Located in rear of the burner top 2 is a vertical backing 3, usually enameled sheet metal. The parts composing the present improvement are preferably made of sheet metal, though they may be constructed of other material without affecting the present improvement.

Extending inward from the top of the backing 3 is what is known and referred to in the art as a top shelf 4. One improvement consists of a reversible support 85 in the form of a vertical angle iron 5 which is located at the outer edge of the backing 2. This shelf has its edge 6 turned downward as shown around its extent.

The supporting bar or angle iron 5 is made so that it is reversible, that is, is capable of being used for a gas range with right hand oven, and is capable of being used with a left hand oven gas range by simply turning it end for end. This angle iron has an inwardly doubled portion 7 and the outer leg or angle 8 of the angle iron is cut out at each end as shown at 9 and 9', the said cut out portions being equal. When the angle iron is used for a right hand gas range as here shown the lower end 10 of the inturned portion 7 rests on the cooking top 2, and the upper cut out portion 9 receives a suitable bracket 12.

This bracket 12 has its angle 13 made of a length to fit between the lower end of the upper cut out portion 9 and the under side of the shelf 4, and the cut out por-

tion of the angle iron and the bracket each have bolt openings 14 and 15 which are the same distance apart to receive the clamping bolts 17, while the flange 6 of the shelf 4 is provided with bolt openings 18 adapted to mesh with the upper openings 14 and 25 of the angle bar and the bracket. It will be understood in this construction that when the angle iron is used for a left hand oven range that the bracket can also be used, since the lower end of the angle iron 5 has its cut out portion 9' of the same length as the cut out portion 9 whereby the said bracket will fit either end of the angle iron. It will also be noted that the angle iron has the bolt openings 14' at its lower end to receive the said clamping bolts 17 when its position is reversed for a left hand oven range.

20 The angle iron 5 which forms a support for the shelf 4 has its leg 19 provided with semi-circular openings 20 and 20', the said openings being located in relation to the cut out portions 9 and 9' exactly the same. The reason for these openings is to register with an opening 21 made in the backing 22 that is located below the cooking top 2 through which the gas supply pipe 23 passes forward to the manifold 24. 25 Therefore the opening 20 of this angle iron when it is turned end for end will also match with the opening 21 for a left hand oven range.

It will also be observed that the rear leg 35 19 of the angle iron has its upper portion provided with bolt openings 25 and the lower portion provided with bolt openings 25'. When the angle iron is used for a right hand oven the upper openings 25 receive securing bolt 26 that pass through the rear edge 6 of the shelf 4 and the backing plate 3. When the angle supporting iron 5 is applied to a right hand oven range the lower bolt openings 25' receive bolts 27 that 40 pass through the said openings, while the openings 14' receive the clamping bolts 28 that pass through the angle bar and the side plate 29. Also the bolts 28 pass through the depending flange 30 of the cooking top 2.

50 The inturned part 7 of the angle iron 5 makes a finish for the stove from the front, its lower end 31 resting on the cooking top 2 and its upper end 32 adapted to receive the lower end of the bracket 12. Therefore this 55 inturned part 7 performs the triple function in its various positions, that is to say, when used for a right hand oven construction the part 32 receives the lower end of the bracket 12 and the part 31 rests above the cooking oven 2. When the angle iron is 60 used for a left hand oven range it is reversed whereby the part 32 acts to rest on the cooking top 2 and the part 31 to receive the lower end of the bracket 12.

65 With the parts in the positions shown in

the drawings the upper cut out portion 9 of the angle iron is exposed, which would leave the bolts passing through the openings 25 also exposed. In order to complete this supporting angle construction an extension member 33 is provided. The part 34 corresponds with the part 7 and the part 35 rests against the backing 3, with the open ended slots 36 receiving the bolts 17. In applying this extension 35 the bolts are applied and the nuts left loose to receive the part 35 after which the said bolts are screwed up thus clamping this extension in position, and it serves to complete the whole structure.

In the construction here shown the shelf bracket 12 needs only to have its edge 13 made of a length to fit between the part 32 and the under part of the shelf 4 when the parts are in the position here shown, or when the angle iron is reversed, then the edge 13 will fit between the cut out part 31 and the under side of the shelf 4. Otherwise no claim is made in this application for special construction of the bracket. A special construction of bracket is provided and will form the subject matter of a separate application.

The cooking top 2 is constructed as before stated with its edge 30 turned downward, and as shown in the drawings this turned down edge is provided near the corner with bolt openings 37 to receive the clamping bolts which pass through the openings 14' and 25'.

A gas range constructed with reversible parts as herein described that are adapted for use with a right and a left hand oven range effects a considerable saving in its construction over the constructions now known to us. It makes a gas range convenient and cheap to construct; it saves the carrying of these parts for the two kinds of ranges in stock, and it produces a gas stove which is very attractive in appearance.

We do not desire to limit ourselves to the exact construction herein shown and described, since variations may be made in the construction without departing from the scope of the invention as defined in the appended claims.

Having thus described the invention what we claim and desire to secure by Letters Patent is:

1. A right or left hand oven range construction, comprising a top shelf, and an angle iron support for the shelf having its opposite ends cut out, whereby it may be used in either a right or left hand oven range by turning it end for end.

2. A right or left hand oven range construction comprising an angle iron having its opposite ends cut out equal distances, whereby it may be used for either a right or left hand oven range construction by

turning it end for end causing either shoulder of the angle iron to rest above the cooking top.

3. A right or left hand oven range construction comprising an angle iron cut out at opposite ends, the edge of the side leg of the angle iron turned inward at an angle between the cut out portions, whereby the angle iron may be applied with the bent portion above the cooking top for either a right or left hand oven range by turning the angle iron end for end.

4. A right or left hand oven range construction comprising a top shelf, an angle iron support for the outer end of the shelf, said angle iron having one leg bent inward at an angle toward the other leg, said bent portion cut away equal distances from both ends of the angle iron, whereby it may be used for either a right or left hand oven range by turning the said angle iron end for end.

5. A right or left hand oven range construction including substantially an L-shaped angle iron with its front leg bent inward toward its rear leg to leave a longitudinal space between its edge and the rear leg, a backing passing in the slot between the said rear leg and the said bent portion of the angle iron, and means for securing the parts together.

6. A right or left hand oven range construction comprising a burner top, an oven at one edge of the burner top, a top shelf, an angle iron having its ends cut out substantially equal distances, whereby the angle iron may be used for a right or left hand oven by turning the same end for end.

7. A right or left hand oven range construction comprising a cooking top, an oven located at one side of the cooking top, a top shelf located over the rear portion of the cooking top and a reversible support for the said shelf located at the outer edge of the backing shelf, the backing, the shelf and the support secured together.

8. A right or left hand oven range construction comprising a burner top, an oven located at one side of the burner top, a vertically arranged shelf at the rear of the burner top, a supporting construction below the burner top, a top shelf, an angle support for the said top shelf having cut out portions substantially the same length at each end thereof, the top of the angle support connected with the shelf and the backing and the lower portion of the angle support connected with the supporting portion of the cooking top, the parts combined for the purpose described.

9. A right or left hand oven range construction comprising a cooking top, a range located to one side of the top, a vertical backing located at the back of the cooking top, a vertically arranged supporting

L-shaped angle bar with the front edge of its side leg bent inward toward the rear leg and cut out substantially the same distance from each end of the supporting bar, the backing passing between the edge of the bent in portion and the rear leg of the angle iron, and means for securing the parts in position.

10. A right or left hand oven range construction comprising a cooking top, an oven located at the side of the top, a vertical backing at the back of the top, a top shelf at the top of the backing, an angle iron support having opposite ends cut away substantially equal distances, a shelf bracket having its vertical edge fitting between the shelf and cut out portion, clamping bolts securing the bracket, the shelf and the angle iron together, whereby the parts are reversible for use in either a right or left hand oven construction.

11. A right or left hand oven range construction comprising a cooking top, an oven located at one side of the cooking top, a supporting frame for the cooking top, a vertical backing at the back of the cooking top, a forwardly projecting horizontal shelf at the top of the backing, and a reversible angle iron support having its side leg bent inward towards the rear leg and separated therefrom to receive the backing, a bracket support for the shelf of a length adapting it to be located between the cut out portion of the angle iron and the shelf, and means for securing the parts in position.

12. A right or left hand oven range construction comprising a cooking top, an oven located at one side of the cooking top, a supporting frame for the cooking top, a backing located at the back of the cooking top, a forwardly projecting shelf located at the top of the backing, a reversible angle iron having its side leg bent inward toward its rear leg, the said inwardly bent portion stopping substantially equal distances from opposite ends of the angle iron, a bracket for the angle iron fitting between the cut out portion and the shelf whereby the angle iron is adapted for use in a right or left hand oven construction by turning the same end for end.

13. A right or left hand oven range construction comprising a cooking top, an oven located at one side of the top, a backing located at the back of the top, a forwardly projecting shelf located at the top of the backing, an angle iron support having its opposite ends provided with cut out portions to receive the fuel feed pipe, whereby the said angle iron is adapted for use with a right or left hand oven by turning it end for end.

14. A right or left hand oven gas range construction comprising a cooking top, an oven located at one side of the cooking top,

- a vertically arranged backing located at the back of the cooking top, a supporting frame for the cooking top, a fuel supply pipe passing from the rear of the construction near its outer edge, an angle iron having its ends cut out substantially equal distances; and the rear leg of each end of the angle iron provided with a cut out portion adapted to receive the said fuel pipe, a top shelf located 5 at the top of the angle iron, and a shelf bracket of a length to fit between the cut out portion and the said shelf, whereby the angle iron is adapted for use in either a right or left hand oven construction.
- 10 15. A range construction comprising a cooking top, an oven at one side of the top, an angle iron having its side leg bent inward toward its rear leg, said bent portion cut away, a top shelf, a backing between 20 the rear edge of the top shelf and the cooking top, and an extension member of a length to fill in the cut out portion of the supporting bar, for the purpose described.
16. A gas range construction comprising 25 a cooking top, an oven at one side of the top, a vertical backing in rear of the top, a forwardly extending shelf at the top of

the backing, a supporting angle bar at the outer edge of the backing, the angle bar having its side leg bent inward towards its 30 rear leg, the bent portion cut away to leave an extended end of the angle bar and an angle member fitting in between the shelf and the end of the cut away bent portion.

17. A gas range construction comprising 35 a cooking top, an oven at one side of the top, a vertical backing at the rear of the top, a shelf extending forward from the said backing, an angular supporting bar at the outer edge of the backing, the side leg of 40 the angle bar bent inward towards its rear leg, the said bent portion cut away, for the purpose described, and an angular extension substantially equal to the cut away portion, the inner leg of the angle having a slot, and 45 a clamping screw passing through the slot and the engaging parts for holding them in position.

In testimony whereof, we hereunto affix our signatures.

HENRY MOECKER, JR.
THEODORE THOMPSON.
OTTO HAMMERMEISTER.
